UNITED STATES PATENT OFFICE.

LOUIS SCHLESINGER, OF MILWAUKEE, WISCONSIN.

SPACING MECHANISM FOR TYPE-WRITING MACHINES.

No. 852,456.

Specification of Letters Patent.

Patented May 7, 1907.

Application filed March 3, 1902. Serial No. 96,553.

To all whom it may concern:

Be it known that I, LOUIS SCHLESINGER, a citizen of the United States, and a resident of the city and county of Milwaukee, State of Wisconsin, have invented certain new and useful Improvements in Spacing Mechanism for Type-Writing Machines, of which the following is a full, clear, and exact description.

In typewriting machines, whether of the style in which the paper carriage or support is movable with respect to the printing mechanism, or that style in which the sheet or book to be written upon is held upon a stationary support over which the printing mechanism is caused to move, it is desirable to provide means whereby the movable part or member may be arrested at any one of a number of "fields" or groups of letter-spaces along its line of travel, as distinguished from mechanism adapted to merely effect the arrest of the movable part or member at any one of a plurality of points arranged at letter-space distances apart as in ordinary tabulating machines.

The primary object of this invention is to provide improved mechanism (independent of tabulator devices, which may or may not be used in conjunction therewith), whereby the operator may cause the arrest of the paper support or movable part at any one of a number of column fields located along the path of travel of the paper support or movable part, and the invention consists in the features of improvement hereinafter described, illustrated in the accompanying drawings and particularly pointed out in the claims at the end of this specification.

Figure 1 is a view in side elevation of a typewriting machine embodying the invention, the left-hand side of the main frame of the machine being broken away. Fig. 2 is a view in horizontal section on line 2—2 of Fig. 1. Fig. 3 is a view of the machine in rear elevation, parts being broken away and parts being shown in vertical section. Fig. 4 is a view in vertical cross-section (from front to rear) through the rear portion of the mechanism, the view being taken on line 4—4 of Fig. 3. Fig. 5 is a detail front view (i. e., looking toward the rear) of the dog carrier at the back of the machine, certain of the adjacent parts being shown in vertical section and other parts being shown in elevation. Fig. 6 is a plan view of the rear portion of the machine. Fig. 7 is a detail inverted plan view of the stop-carrying bar. Fig. 8 is a detail view in

transverse section of the stop-carrying bar. Fig. 9 is a detail view in central longitudinal section through one end of the stop-carrying bar. Fig. 10 is a plan view of the rear portion of the top of the main frame and of certain parts carried thereby, the carriage mechanism being omitted and the pawl carrier and certain adjacent parts being shown in horizontal section. Fig. 11 is a view in vertical cross-section (i. e., from front to rear) through the rear portion of the machine, this view being taken on line 11—11 of Fig. 3. Fig. 12 is a view in vertical cross-section (i. e., from front to rear) through the rear portion of the machine, parts being omitted, certain parts being shown in elevation and the tabulator mechanism being shown in position.

In the accompanying drawings the invention is shown as applied to the well-known Remington No. 6 typewriter, although it will be understood that with more or less modification it may be used in connection with various other styles of typewriting machines. I wish it distinctly understood, therefore, that while I have illustrated in the accompanying drawings and shall now describe what I regard as the preferred embodiment of the invention, extensive modifications may be made by the skilled mechanic without departure from the scope of the invention, and features of the invention may be employed without its adoption as an entirety.

A designates the frame of a Remington typewriter, upon the top-plate of which is mounted the usual paper-carriage B that is provided with the platen C whereon is supported the paper to be printed. The paper-carriage B is shown as provided at its rear with the usual pivoted rack bar D, the downwardly-facing teeth of which are in normal engagement with the teeth of the escapement pinion D'. This pinion D' is mounted in the ordinary manner upon the inner end of a shaft d at the back of the top-plate of the machine, the rear end of the shaft carrying the usual escapement ratchet wheel d', with the teeth of which engage the escapement pawls or dogs d² and d³ that are vibrated by a lever d⁴, as will readily be understood by those familiar with this style of machine. The rack bar D is pivotally supported in the usual manner so that it may be disengaged from the teeth of the pinion D'. As shown, the rear part of the carriage B is provided with bearing rolls b that travel upon the back rail b' which extends from side to side of the

machine across its top, and these bearing rolls b are journaled in the back part of the frame of the carriage B. From the carriage B projects rearwardly an arm B' that engages a rail b^2 extending across the top-plate of the main frame at the rear of the carriage and beneath this rail is mounted the usual bar b^4 whereby the margin-stops will be carried. The mechanism thus far described is that found in the familiar No. 6 typewriter and without more precise description its construction and operation will be readily understood by those familiar with this class of machine.

15 To the back of the paper-carriage B is connected a frame E (see Figs. 1 and 6), the inner depending arms e of which are bolted to the rear of the paper-carriage as at e' . As shown, the frame E is formed with rearwardly-extending arms e^2 that serve to carry a stop-bar F. The stop-bar F is preferably adjustably attached to the frame E and for this purpose the arms e^2 of the frame are preferably formed with slots e^3 through which 20 pass the screws e^4 that enter threaded holes in the ends of the bar F. The stop-bar F is preferably formed upon its front and rear edges with notches located at letter-space distance apart, these notches being adapted 25 to receive the bifurcated portions of the column field-stops G and to receive also the bifurcated portions of the denominational stops H, if these latter stops be used. The purpose of adjustably supporting the stop-bar F is to enable its notches to be caused 30 to register accurately with the letter-space scale of the machine and it will be readily seen that by loosening the screws e^4 at the ends of the stop-bar F, the bar may be shifted 35 lengthwise to effect the required adjustment.

In the preferred embodiment of the invention, the construction of stop-bar is that illustrated more particularly in Figs. 6-9 of the drawings, the purpose of this construction being to provide means for locking the column-stops and denominational-stops against accidental displacement from the stop-bar. As shown, the stop-bar F is formed upon its under side with a longitudinal dove-tailed channel f adapted to receive a correspondingly dove-tailed locking plate F'. One end of this locking plate F' is provided with a pin or offset f^2 that is engaged by the notched end of a lever F² that is pivoted as at f^2 within a slot formed in the end 45 of the stop-bar F. The locking plate F' is formed upon one side with notches and ribs corresponding with the notches and ribs of the stop-bar F and adapted to aline there- 50 with when the column-field stops and the denominational stops are to be placed in position; but by shifting the lever F² the locking plate F' may be moved slightly lengthwise so as to cause the ribs of this locking plate 55 to come opposite the notches of the stop-bar

60 E. By reference to Fig. 4 of the drawings it will be seen that the column-field stops G (and the same is true also of the denominational stops H) are formed with notches g and when the locking plate is shifted as last 65 described, the ribs or projections of this locking plate will enter the notches g of the stops G (and as well also the notches of the denominational stops H) and will thus prevent the movement of the stops from the position in which they have been set. When, 70 however, it is desired to remove the stops, the lever F² will be shifted so as to bring the ribs or projections of the locking plate F' in vertical line with the ribs of the stop-bar F, 75 thereby permitting the column-field stops or the denominational stops to be withdrawn. The denominational stops H are designed to co-operate with the tabulating mechanism to be hereinafter briefly described, and the 80 column-field stops are designed to co-operate with the mechanism to be next described, whereby the arrest of the paper-carriage may be effected at any one of several predetermined points along the line of print. 85

By reference more particularly to Figs. 1, 2 and 3 of the drawings it will be seen that adjacent one side of the main frame of the machine extend two key-levers J and K. As shown, the key-lever J is journaled in the 90 usual manner upon a depending rib j at the back of the machine, and the key-lever K is pivoted as at k to the rear end of the lever J, both of these levers J and K being forced normally upward by the usual plate-spring 4 95 that is mounted upon a bar 5 extending transversely of the machine near its back.

A series of field-stop finger-keys M, M', M², M³, M⁴ mounted one above the other at 100 one side and transversely of the keyboard, with their upright stems m' extending through fixed sleeves m^2 and resting upon the forward end of lever K to be normally upheld thereby. Keys M, M', M², M³, M⁴ are arrested, when pressed down, by the upper 105 ends of sleeves m^2 , which thus act as stops and which are so graded that the several keys will have substantially a uniform throw. If any key is depressed a uniform throw is 110 imparted to lever K, which operates the release and may be termed the release lever. The adjacent lever J has at its forward end a series of graded steps j' with which engage 115 collars m adjustably threaded on stems m' of keys M, M', etc. Collars m are arranged at 120 varying distances above the respective steps j' so that a variable throw will be imparted by the several keys to lever J, which controls the stop dog and may be termed the dog-operating lever. In other words, the several 125 keys actuate dog-operating lever J with varying degrees of lost motion to impart thereto different extents of depression, whereby the stop-dog may be variably shifted, as will presently appear. 130

To the back portion a^3 of the main frame (see Figs. 1 and 2) is fastened a frame or plate 6 having at its ends upwardly-extending arms 7 in which is journaled a shaft 8. On this shaft is loosely mounted a sleeve 9 having fixed thereto a rearwardly projecting arm 10. To the shaft 8 is fixed a lever 12, the inner end of which is formed with a slot 13 (shown by dotted lines in Fig. 1) and has pivotally connected thereto the upper end of a link 14. The lower portion of the link 14 (see Fig. 3) is formed with a slot 15 through which passes a headed pin 16 that connects the link to the lever J. The lower end of the link 14 is turned inwardly as at 17 and formed with a threaded hole through which passes an adjusting screw 18 and preferably a threaded jam-nut 19 holds the screw 18 in place when it has been adjusted, the screw 18 being arranged to contact with the lower edge of the lever J. The purpose of the screw 18 is to accurately determine the movement imparted by the lever J to the parts controlled thereby. From the outer face of the lever K projects a pin 20 adapted to enter a slot 21 that is formed in the lower portion of a link 22, the upper portion of which link is bent rearwardly and is pivotally connected as at 23 to the rear end of a rock-arm 24 that is fixed to the sleeve 9 revolvably mounted on the shaft 8. The lower end of the link 22 is bent inwardly beneath the lever K, as shown in Fig. 3, and is formed with a threaded hole to receive a set-screw 25 that is furnished with a jam-nut 26, the upper end of the set-screw 25 being adapted to contact with the lower edge of the lever K. To one side of the lever K is attached a plate-spring 27, the free end of which enters a notch in the edge of the link 22 (see Fig. 1), the spring 27 thus serving to hold the link 22 in its uppermost position. By adjusting screws 18 and 25, which engage respectively with levers K and J, the extent of movement of the parts controlled by the levers, may be accurately determined.

From the foregoing description it will be seen that when any one of the finger-keys M, M', etc., is depressed, it will force down both the operating-lever J and the releasing lever K and the operating lever will carry downward the link 14 and by means of the rock-arm 12, will cause the shaft 8 to rock, while at the same time the downward movement of the lever K will force downward the link 22, which, being connected by the arm 24 with the sleeve 9, will cause the sleeve to turn about the shaft 8 and will cause the rock-arm 10 to move downward. By reference more particularly to Figs. 2, 3 and 4 of the drawings, it will be seen that the shaft 8 has connected thereto a rock-arm 30, to the free end of which is pivotally connected as at 31, the lower end of a rod 32.

The rod 32 extends upward through a bracket 33 that rises from the plate or frame

6 and the upper end of the rod has fixed thereto a plate O having ratchet teeth o on one of its edges. As shown, the plate O is movable longitudinally between a plate O' and a plate O², the plate O' having corresponding ratchet teeth on one edge. The plates O' and O² are connected together and constitute a carrier for the dog P that is preferably formed separate from the plates and is adjustably connected thereto by a set-screw p that passes through a slot p' of the dog P and enters a threaded hole in the upper end of the plate O². To more securely hold the dog P in position, it is preferably formed with teeth adapted to engage similar teeth o^2 formed on the face of the plate O². By adjusting the dog P in the direction of the line of print by means of the set-screw p, the position of the dog for accurately arresting the travel of the carriage can be determined, it being understood that the dog P is adapted to contact with the depending lower ends of the column-field stops G above it, as will presently more fully appear. The plates O' and O² are mounted to slide within a frame R (see Figs. 3 and 4) the back of this frame being formed with a slot r through which passes a screw 35 that enters the plate O'. The frame R has a horizontally-projecting portion r^2 that rests upon and is bolted to the rear of the top-plate 95 of the main-frame A (see Fig. 4), and the upper part of the frame R is formed with a rearwardly-projecting portion r^3 that rests upon and is bolted to a bracket a^4 (see Figs. 4 and 6) that is fastened to a back rod b^2 extending 100 across the top of the main-frame of the machine at its rear. The downward movement of the dog P and dog holder O' O² is limited by the engagement of the screw or stud 35 with the lower end of the slot r . The plate O 105 is provided at its lower end with a shoulder O³ that is arranged to engage the lower edge of the plate O² when the rod 32 is shifted vertically. Normally this shoulder is spaced, as shown in Fig. 4, slightly apart from the 110 lower edge of the plate O². To the upper part of the rod 32 is fixed a collar 36 to which is attached the upper end of a coil-spring 37, the lower end of this spring being attached as at 38 to the bracket 33 (see Fig. 3), and this spring 37 serves to draw downward the plate O to normal position. If found necessary a second spring may be attached to the dog-carrier O' O² to hold it in lowermost position. 115

By reference to Fig. 3 of the drawings, it 120 will be seen that the column-field stops G have their lower ends depending to different distances from the bottom of the stop-bar F and the stops will be arranged progressively, the longest stop G being nearest the right-hand end of the paper-carriage while the shortest stop is nearest the left-hand end of the paper-carriage. Now by reference more 125 particularly to Figs. 1-5 of the drawings, it will be seen that if one of the finger-keys, M 130

for example, be depressed, it will force downward the dog-operating lever J and lever K. The operating lever J will rock the shaft 8 and will cause the rod 32 to lift the plate O vertically. When the lost motion between the shoulder O³ at the base of the plate O, and the lower edge of the plate O² is taken, the dog-carrier is lifted, thus raising the dog P, and inasmuch as collar m of the finger-key 10 M is normally in contact with the dog-operating lever J, it will impart a long movement to the dog-operating lever and will consequently lift the dog-carrier and dog P to their highest point where the dog will be in position to engage the shortest of the column-field stops G on the stop-bar F. On the other hand, if one of the other finger-keys, M⁴ for example, be depressed, it will impart a much shorter vertical movement to the 20 dog-carrier and dog P, both because of the greater distance of the key M⁴ from the fulcrum of the dog-operating lever J, and also because of the location of the collar m that contacts with the lever J at a distance from 25 the edge of the lever J. In other words, the varying degrees of lost-motion between the finger-keys and the dog-operating lever insure different extents of movement to the dog-carrier and dog P and hence cause the 30 dog to be lifted the different distances necessary to enable it to properly engage the different column-field stops G upon the stop-bar F. In this way the operator, by depressing any one of the finger-keys M, M', etc., 35 can cause the paper-carriage to be arrested at any predetermined point of its travel.

In order to retain the dog P in raised position after it has been lifted by the depression of any one of the finger-keys M, M', etc., and 40 thus avoid the necessity of the operator holding his finger upon the depressed key, I provide a check pawl 40 that is pivotally mounted as at 41 upon the frame R, a coil-spring 42 serving to normally force the upper end of 45 the pawl 40 into engagement with the teeth o of the dog-carrier. Hence it will be seen that when the dog-carrier and dog P are lifted in manner before described, the pawl 40 will engage the teeth o and will temporarily hold the dog-carrier and the dog actuating member in raised position after the release of the finger-key whereby the lifting of the dog has been effected. In order to effect the free run of the carriage from right to left 50 after the dog P has thus been lifted to position to engage one or another of the column-field stops G, I prefer to employ the mechanism next to be described.

To the rock arm 10 that projects rearwardly from the sleeve 9 (see Figs. 1, 2 and 3) is pivotally connected as at 45 the lower end of a rod 46 that is preferably provided with a turn-buckle 47 for adjustment, and the upper end of the rod 46 is flattened and 55 formed with a slot 48 through which passes

a headed pin 49 that projects from the tail of a release pawl 50. The pawl 50 is pivoted as at 51 upon an arm r⁵ depending from the frame R and the upper end of the pawl 50 is formed with a shoulder 52 adapted to engage the rear end of a release lever T whereby the carriage rack D (see Figs. 6 and 10) will be lifted from engagement with the escapement pinion D'. The release lever T is pivotally mounted upon a rod t in a bracket that 70 rises from the plate r² of the frame R (see Figs. 4 and 10), and the inner end of the release lever T is forced normally downward by a spring t'. The inner end of the release lever T carries a release plate t² that extends beneath the carriage rack bar D, so that when the inner end of the release lever T is raised by the depression of its outer end, it will throw the carriage rack D from engagement with the escapement pinion D' and thus permit the carriage to run free from right to left until the dog P that has been raised by the depression of one of the finger-keys M, M', etc., contacts with its corresponding column-field stop G. To the rear end of the release 80 lever T is connected the upper end of a coil-spring 55; the lower end of which spring is attached to a rod 56 (see Figs. 1, 3 and 11), the lower end of this rod 56 being attached to an offset arm 57 that projects laterally 90 from the lower end of the rod 46. Preferably, the upper end of the coil-spring 55 is connected to the rear end of the release lever T (see Fig. 11) by means of a U-shaped plate 55^a that straddles the release lever, and 95 through the crown of this plate 55^a, that has a threaded hole therein, projects a set-screw 55^b adapted to bear against the upper edge of the release lever T. By means of this set-screw 55^b the tension of the spring 55 can 100 be readily controlled. Hence it will be seen that when one of the finger-keys M, M', etc., has been depressed, thereby pressing downward the forward end of the levers J and K and raising the dog-carrier and dog P in 105 manner hereinbefore described, the rock-arm 10 will be turned downward by the link 22 rocking the sleeve 9. This downward movement of the rock-arm 10 will cause the rod 56 to place the spring 55 under tension, 110 thereby exerting a pull upon the rear end of the release lever T. Inasmuch, however, as the check pawl 40 is at such time in engagement with the rear end of the release lever T, the tension placed upon the spring 55 does 115 not move the release lever T until the rock-arm 10 has so far moved downward with the link or rod 46 as to cause the upper end of this rod to engage with the pin or screw 49 and thus swing the check pawl 40 about its 120 pivot point 51 until the shoulder 52 of the pawl is disengaged from the rear end of the release lever T. In other words, the slot 48 in the upper end of the rod 46 allows a lost-motion of the pawl-releasing mechanism, 125

while the spring 55 is being placed under tension in readiness to shift the release lever T. This release of the check pawl 50 (determined accurately by adjusting turn-buckle 47) will occur at the time that the dog-carrier and dog P reach the limit of their upward movement, when the dog P will be in position to engage its corresponding stop of the stop-bar F; and when the dog has been thus raised 5 and the shoulder 52 of the check pawl 50 withdrawn from beneath the rear end of the release lever T, the spring 55 will draw downward the rear end of the release lever, thereby causing its inner end to lift the rack-bar D of the paper-carriage from engagement with the escapement pinion D', so that the carriage may run free from right to left until its movement is checked by the engagement 10 of one or another of the column-field stops 15 with the raised dog P. By this arrangement, the escapement release occurs at the end of the downward movement of lever K and rod 46 and this movement, as stated, is uniform if every key is depressed, so that the 20 release is invariably actuated at the end of the down stroke of any key, at which point the dog has been shifted to the required height for arresting the carriage at the desired "field." In other words, in spite of the 25 variable shift imparted to lever J and dog P by keys M, M', etc., a uniform shift is imparted to lever K, so that the release is invariably operated, but not until the end of such uniform throw and not until dog P has been 30 raised to the desired height. A premature release of the escapement is thus prevented and carriage B is invariably arrested at that stop corresponding to the key depressed.

The check pawl 50 is normally forced to 35 ward the position to engage the rear end of the release lever T by a spring 58, one end of which is connected to the plate r^5 (see Fig. 3), while the opposite end of this spring bears on the tail of the pawl 50. As soon as the 40 release lever T has thus been drawn down to disengage the rack-bar of the paper-carriage from the escapement pinion, a pin 60 depending from a lever 61 (see Figs. 3 and 6) will swing above the rear end of the release 45 lever T and hold the lever in the depressed position notwithstanding the operator may have lifted his finger from the finger-keys M, M', etc., whereby the operation of the parts has been effected. As shown, the lever 61 is 50 pivoted upon a stud 62 that rises from the plate r^2 of the frame R and this lever 61 is provided with an arm 63 that extends rearwardly to a position in front of an arm 64 (see Figs. 10 and 12) that extends upward 55 from the rocking arm d^4 whereby the escapement pawls or dogs are carried. A spring 65 tends to normally turn the lever 61 so as to cause the pin 60 to swing over the rear end of the release lever T.

60 Assuming the dog-carrier and the dog P to

have been raised by one of the keys M, M', etc., as above described, it will be seen that the paper-carriage will run freely from the right toward the left of the machine, until the column-field stop G corresponding to the 70 point to which the dog P has been raised, contacts with said dog and thus checks the further run of the carriage. If, now, the operator depresses one of the usual finger-keys of the key-board, as for example in printing 75 a letter or a numeral, such depression of the finger-key will cause the escapement mechanism of the machine to be actuated in the usual manner and at the same time will cause the arm 64 (see Figs. 10 and 12) to swing forward and thus turn the lever 61 until the pin 60 passes from the rear end of the releasing lever T. This swinging movement of the lever 61 will cause its arm that carries the pin 60 (see Fig. 5) to contact with the lower end 80 of the pawl 40, thereby swinging this pawl about its pivot point 41 and releasing the pawl from engagement with the teeth o of the dog-carrier. When the pawl 40 is thus disengaged from the dog-carrier the spring 37 85 (see Fig. 3) will retract the dog-actuating means and permit the dog-carrier and dog to return to normal position and will allow the paper-carriage to be advanced from right to left as the usual keys of the machine are 90 operated to print their characters.

By reference more particularly to Figs. 4, 5 and 10 of the drawings it will be seen that the inner face of the dog-carrier (i. e., the plate O') is formed with a cam-shaped recess o^5 100 into which normally projects the free end of an arm 70 that is pivotally mounted upon a stud 71 that rises from the plate r^2 of the frame R, the free end of the arm 70 being adapted to cooperate with the lower edge of the slot o^5 . A spring 72 serves to force the arm 70 normally toward the dog-carrier. Upon the arm 70 is fixed a detent arm or pawl 75 of spring-metal that is adapted to be shifted laterally by the arm 70 over and into engagement with the teeth of the escapement ratchet-wheel d in order to check any "over-throw" movement of the ratchet wheel after the release lever T has disengaged the rack-bar D from the escapement pinion D' on the inner end of shaft d in manner before described. In the normal position of the dog-carrier, the free end of the arm 70 is within the notch o^6 but when the dog-carrier is lifted, its end is struck by the inclined face o^6 of the notch and the arm 70 is swung forwardly, thereby causing the detent 75 to swing over and into engagement with the teeth of the ratchet escapement wheel d' on the outer end of shaft d . As soon however, as the dog-carrier is released and caused to descend, the spring 72 will reversely shift the arm 70 and detent 75, so as to cause the detent to pass from engagement with the escapement ratchet wheel d' . 115

120

125

130

- In order to prevent the too rapid movement of the paper-carriage from right to left when the dog-carrier and dog P have been lifted as before described, I prefer to employ 5 the brake mechanism next to be described, reference being had more particularly to Figs. 3 and 4 of the drawings. Within brackets 80 that rise from the transverse bar a^4 at the back of the machine, is pivotally 10 supported a brake-lever W, the upper arm of which extends beneath the horizontal plate of the frame E and carries a friction roll w adapted to bear against the under side of such plate. The lower arm of the brake-lever W is bent laterally, as shown in Fig. 3, and carries a grooved roller 82 adapted to bear against a brake-arm 83 that is clamped as at 84 to the dog-carrier rod 32. The upper portion of the brake-arm 83 extends for- 15 wardly or inwardly, as shown in Fig. 4, and its extreme upper part is cut-away as at 85. The roller 82 rests normally within this cut-away part 85 of the brake-arm 83 and when in such position the friction roller w exerts 20 no braking action upon the frame E of the paper-carriage. As soon, however, as one of the finger-keys M, M', etc., is depressed to raise the dog-carrier and the dog P, the upward movement of the rod 32 causes the 25 brake arm 83 to bear upon the roller 82, thereby forcing inward the lower arm of the brake lever W and swinging upward its upper arm so that the friction roll w shall bear with more or less force against the under side 30 of the frame E and thus check the too rapid movement of the paper-carriage. The lost motion between the plate O and the dog-carrier insures that the brake will be applied before the dog is shifted and before the carriage 35 starts on its run. As has been already shown (see Fig. 3), the column-field stops G are disposed upon the stop-bar F with the shortest stops nearest the left-hand end of the paper-carriage. Hence the dog-carrier and 40 the dog P will be lifted to their greatest extent (i. e., by the key M or M') when the carriage is to have its shortest free run from right to left. In this short free run of the paper-carriage but a slight pressure of the friction-roll w is necessary to check the 45 too rapid movement of the carriage but when the carriage is to have a longer run from left to right, a more forcible pressure of the friction roll w upon the frame E is required. 50 Now by reference to Fig. 4 it will be seen that when the dog-carrier and the dog P are lifted but a short distance, which will be the case when the carriage is to have a long free run, that part of the brake arm 83 immediately 55 below the cut-away space 85 will bear upon the grooved roller 82 and consequently the brake lever W will receive its greatest shift and the friction roll w will bear most forcibly 60 against the under side of the frame E. On the other hand, when the dog-carrier and the
- dog P are lifted to their greatest extent, which will be the case when the carriage is to have its shortest free run, the lower part of the brake-arm 83 will bear against the grooved roll 82 and as the inner edge of this lower part of the brake arm 83 inclines rear- 70 wardly, it is obvious that a less extent of movement will be imparted to the brake-lever W and the friction roll w will be caused to bear less forcibly against the under side of the frame E. Preferably, the friction roll w will be of soft rubber or like elastic material capable of being expanded in one direction. Preferably, the spindle w' of the friction roll w , which is adjustably threaded into the end 80 of the arm W, carries a dished plate w^2 which is smaller than and bears against the side of the roll w . By adjusting the spindle in axial direction the plate will bear against the central portion of the roll so that the latter 85 will be expanded in radial direction to increase its frictional bearing on the bar E.
- From the foregoing description it will be seen that by setting the column-field stops G at predetermined points along the stop-bar F, the operator, by depressing any one of the finger-keys M, M', etc., can cause the free run of the carriage toward the left, arresting it at the column-field stop corresponding to the finger-keys M, M', etc., that may be depressed. Thus for example, if letters are to be written upon an ordinary printed letter-sheet, the operator will need to insert the date, the name and address of the party to whom the letter is to be written, etc., usually in about the following form:

January 15, 1902.

J. Smith, Esq.,
150 Madison street,
Chicago,
Illinois.

105

Dear Sir:—Your favor of the 10th inst.,
duly received, etc.

Before writing such a letter the operator 110 will set the longest column-field stop G, say at a point on the stop-bar F corresponding to the point designated by the numeral "45" on the letter-space scale and at such point the operator will begin to print the date, viz., 115 January 15, 1902. The operator will set the shortest column-field stop at a point on the stop-bar F corresponding to the point designated by the numeral "5" on the letter-space scale and at such point will begin to 120 print the name, viz., J. Smith, Esq. At a point on stop bar F corresponding to the point designated by the numeral "10" on the letter-space scale, the operator may set the next shortest column-field stop G and at such 125 point will begin to print the city address, viz., 150 Madison street. At a point on the stop-bar F corresponding for example to the point designated by the numeral "15" on the letter-space scale, the operator will set the 130

next shortest column-field stop G and at such point will begin to print the city address viz., Chicago; and at a point of the stop-bar corresponding for example to the point designated by the numeral "20" upon the letter-space scale, the operator will set the next shortest column-field stop G and at such point will begin to print the State address, viz., Illinois. The operator may begin to print the words "Dear Sir" in line with the name "J. Smith, Esq." and may begin to print the words "Your favor of the 10th inst., duly received" etc., on line with the point at which the city address, viz., "Chicago" has been printed.

It will thus be seen that the operator, by depressing the finger-keys M, M', etc., can cause the free run of the paper-carriage from right toward the left, so that the necessity of advancing the carriage either by the usual manual release or by the actuation of the space-bar is avoided. It will be understood of course that the position of the column-field stops G upon the stop-bar F will be varied corresponding to the character of the work to be done.

In Figs. 1, 2, 6 and 12 of the drawings I have shown my invention as applied to a typewriting machine in connection with which a tabulator mechanism is used, this tabulator mechanism being of the type commonly known as the "Gorin" tabulator. As shown, this tabulator mechanism comprises a series of vertical bars X mounted upon a frame Y at the back of the machine, the bars X being pivoted upon a transverse rod x, as clearly shown in Fig. 12. The frame Y is connected at its lower end to the base portion of the machine frame and at its upper end is connected to the part "a" by the pin "a". The lower ends of the tabulator bars X are connected to push rods X' that extend beneath the base of the machine from back to front and are held in the normally retracted position shown in Figs. 1 and 2, by the coil-springs x', these several push rods bearing at their ends finger-keys X². The upper ends of the tabulator bars X pass through the upper portion of the frame Y (see Fig. 12) so that when any one of the several finger-keys X² is forced inward, the upper end of the corresponding bar X will be swung forward into position to engage a rearwardly-projecting portion of the denominational stop H, these denominational stops H being arranged upon the stop-bar F in the usual manner at any predetermined points thereon.

To the upper portion of the side-bars of the frame Y are pivoted the arms of a yoke-shaped bar 90, the crown 91 of this bar extending in front of the several tabulator bars X (see Figs. 1 and 12). To one of the arms of the yoke-shaped bar 90 is connected a releasing arm 92, the front end of which is bent downwardly as at 93 and arranged to

unlock the pawl 50 (see Fig. 5) and to shift release-lever T. The end-portion or extension 93 of the release arm 92 is formed upon its side with an inclined face 94 adapted to contact with an offset 95 that projects laterally from the end-portion of the pivoted lever 61, which end-portion carries the pin 60 that is adapted to extend over and hold depressed the release lever T when the dog-carrier and the dog have been lifted in manner before described. Hence it will be seen that if, by the depression of one of the finger-keys M, M', etc., the dog-carrier and the dog P have been lifted, and the pin 60 has been caused to swing above the top of the release lever T, as hereinbefore described, the free run of the carriage to a predetermined point corresponding to the finger-key depressed, will be effected. Then if the operator desires to print a line of figures composing a number at such point, he will depress one of the tabulator keys X² in order to further advance the paper-carriage to the exact point corresponding to the denomination of the first figure of the number to be printed. When the tabulator key X² has been thus depressed, it will throw forward the corresponding one of the tabulator bars X and as this bar is thus thrown forward, the yoke-shaped bar 90 will be forced inward, thereby causing the arm 92 (see Figs. 1 and 5) to be depressed, thus causing the cam-shaped surface 94 of the end-portion 93 of this arm 92 to contact with the extension 95 on the side of the lever 61 until the pin 60 is forced laterally from above the release lever T, which is then held down by arm 92. This lateral movement of the lever 61 will not only permit the outer end of the lever T to rise when released by arm 92 and thus cause the escapement rack and pinion of the carriage to re-engage but will also cause it to move inward the lower end of the check-pawl 40 so as to disengage this pawl from the teeth o of the dog-carrier and thus permit the dog-carrier and the dog P to drop to normal position; after which the printing of the figures comprising the number may be proceeded with in the usual manner.

One marked advantage incident to the brake-mechanism hereinbefore described, is that the variation in the action of the brake is effected mechanically, as distinguished from that type of brake mechanism in which the variation in the action of the brake is dependent upon the varying pressure that may be applied to the brake by means of the operator's hand.

From the foregoing description it will be seen that the operation of the escapement rocker, which is controlled in the usual manner by the universal bar, effects an automatic release of the locking means for the stop-dog P and feed-rack; that the stop-dog and feed-rack are released on the down stroke of the

universal bar and this does not therefore interfere with the letter-space movement of the carriage, which is effected during the up or return stroke of the key actuated and at a time when the release of the parts has been automatically effected.

It will be understood that broadly considered the stops P, G, H and X are tabulating stops; that more specifically considered, the stop P is an arresting stop or dog or column-stop dog; that more specifically considered, the stops G and H are column-stops or column-field stops, the former co-operating with the dog P and the latter with the stops X, and that the latter, when more specifically considered, are denominational stops, and these various stops are thus differently designated in the claims.

While I have described the column-stop mechanism and denominational-stop mechanism in use in conjunction with one another, it will be understood that each mechanism may be employed without bringing the other into operation. Thus, for instance, the column-stop may be used independently of the denominational-stop mechanism where columnar fields alone are to be secured, and the denominational-stop mechanism may, when desired, be employed without bringing the column-stop mechanism into operation, so that each mechanism may be operated independently of the other to perform the work for which it is particularly adapted. When the column-stop mechanism is employed, a single actuation of a key M, M', M², etc. is all that is necessary to project the stop P into the path of the proper column-stop G and release the carriage and lock the feed-rack and projected stop P in their abnormal positions; these parts being automatically released at the next actuation of a character key or the space key. If, on the other hand, the denominational-stop mechanism is to be employed alone, it is only necessary to actuate push-keys X² to arrest the carriage at the proper denominational position within the columnar field determined by the location of the stops H. In either event no preliminary operation of an auxiliary key is necessary to effect the proper operation of the tabulating mechanism, whether it be the column-stop mechanism or the denominational-stop mechanism. It should also be noted that the locking devices for the column stop mechanism are arranged to be released, not only by the operation of one of the type bars or space bar of the machine, but also by the operation of the denominational stop mechanism. By this arrangement, after the column stop mechanism is operated to bring the carriage to the desired column field, either the printing mechanism of the machine or the denominational stop mechanism may be at once operated, and in either case no preliminary opera-

tion is necessary to first unlock the column stop mechanism.

It is manifest that the precise details of construction above set forth may be varied within wide limits without departing from the spirit of the invention and that features of the invention may be employed without its adoption as an entirety.

Having thus described my invention what I claim as new and desire to secure by Letters Patent is:—

1. In a spacing mechanism for typewriting machines, the combination with a paper-support and with a printing mechanism, one of said parts being movable with respect to the other in the direction of the line of print, and with columnating mechanism whereby said movable part may be arrested at a predetermined column-field upon the paper, and with denominational stop mechanism whereby the orderly printing of rows of figures or the like may be effected, of means whereby the operation of said denominational stop mechanism shall restore said columnating mechanism to normal position.

2. In a spacing mechanism for typewriting machines, the combination with a paper-support and with a printing mechanism, one of said parts being movable with respect to the other in the direction of the line of print, of means for arresting the travel of said movable part embracing two members, one of said members comprising a plurality of column-field stops mounted upon one of said parts, and the other of said members comprising means for dogging said stops and being mounted upon the other of said parts, one of said members being movable to engage the other, denominational stop mechanism whereby the orderly printing of rows of figures or the like may be effected and means independent of the denominational stop mechanism and having lost-motion connections for variably actuating said movable member to effect the engagement of said dogging means and any predetermined one of said column-field stops.

3. In a spacing mechanism for typewriting machines, the combination with a paper support and with a printing mechanism, one of said parts being movable with respect to the other in the direction of the line of print, of means for arresting the travel of said movable part embracing two members, one of said members comprising a plurality of column-field stops mounted upon one of said parts, and the other of said members comprising means for dogging said stops and being mounted upon the other of said parts, one of said members being movable to engage the other, and key mechanism whereby said dogging mechanism and said column-field stops may be caused to engage, said key mechanism comprising a stepped lever connected with the movable part of said column-

field stop mechanism and a plurality of individual keys provided with adjustable parts for engaging the stepped portions of said lever.

5. 4. In a spacing mechanism for typewriting machines, the combination with a paper-support and with a printing mechanism, one of said parts being movable with respect to the other in the direction of the line of print and with escapement mechanism intermediate said parts and with an escapement release for permitting the free travel of the movable one of said parts, of means for arresting the travel of said movable part embracing two members, one of said members having a plurality of column-field stops mounted upon one of said parts and the other of said members comprising means for dogging said stops and being mounted upon the other of said parts, 10 one of said members being movable to engage the other, means whereby said dogging mechanism and said column-field stops may be caused to engage and whereby said escapement release is actuated, and adjusting means whereby the time of the actuation of the escapement release may be accurately determined.

5. In a spacing mechanism for typewriting machines, the combination with a paper-support and with a printing mechanism, one of said parts being movable with respect to the other in the direction of the line of print and with escapement mechanism intermediate said parts and with an escapement release for permitting the free travel of the movable one of said parts, of means for arresting the travel of said movable part embracing two members, one of said members having a plurality of column-field stops mounted upon one of said parts and the other of said members comprising means for dogging said stops and being mounted upon the other of said parts, one of said members being movable to engage the other, key mechanism whereby said dogging mechanism and said column-field stops may be caused to engage, said key mechanism comprising plural levers, one of which is connected with the movable member of the column-field stop mechanism and the other of which is connected with means for operating the release to permit the free travel of the paper-support or movable part, and adjusting means intermediate the escapement release and the lever whereby it is operated.

6. In a spacing mechanism for typewriting machines, the combination with a paper-support and with a printing mechanism, one of said parts being movable with respect to the other in the direction of the line of print and with escapement mechanism intermediate said parts and with an escapement release for permitting the free travel of the movable one of said parts, of means for arresting the travel of said movable part, embracing two mem-

bers, one of said members having a plurality of column-field stops mounted upon one of said parts and the other of said members comprising means for dogging said stops and being mounted upon the other of said parts, one of said members being movable to engage the other, key mechanism whereby said dogging mechanism and said column-field stops may be caused to engage, said key mechanism comprising plural levers, one of which is connected with the movable member of the column-field stop mechanism and the other of which is connected with means for operating the release to permit the free travel of the paper-support or movable part and adjusting means intermediate the movable member of the column-field stop mechanism and the lever whereby said movable member is actuated.

7. In a spacing mechanism for typewriting machines, the combination with a paper-support and with a printing mechanism, one of said parts being movable with respect to the other in the direction of the line of print and with escapement mechanism intermediate said parts and with an escapement release for permitting the free travel of the movable one of said parts, of means for arresting the travel of said movable part, embracing two members, one of said members having a plurality of column-field stops mounted upon one of said parts and the other of said members comprising means for dogging said stops and being mounted upon the other of said parts, one of said members being movable to engage the other, key mechanism whereby said dogging mechanism and said column-field stops may be caused to engage, said key mechanism comprising plural levers, one of which is connected with the movable member of the column-field stop mechanism and the other of which is connected with means for operating the release to permit the free travel of the paper-support or movable part, and adjusting devices intermediate said levers and the parts actuated thereby, respectively.

8. In a spacing mechanism for typewriting machines, the combination with a paper-support and with a printing mechanism, one of said parts being movable with respect to the other in the direction of the line of print and with escapement mechanism intermediate said parts and with an escapement release for permitting the free travel of the movable one of said parts, of means for arresting the travel of said movable part embracing two members, one of said members having a plurality of column-field stops mounted upon one of said parts and the other of said members comprising means for dogging said stops and being mounted upon the other of said parts, one of said members being movable to engage the other, key mechanism whereby said dogging mechanism and said

column-field stops may be caused to engage, said key mechanism comprising means connected to the movable member of the column-field stop mechanism and an adjusting device intermediate the key mechanism and the escapement release whereby the time of the operation of said release may be accurately determined.

9. In a spacing mechanism for typewriting machines, the combination with a paper-support and with a printing mechanism, one of said parts being movable with respect to the other in the direction of the line of print and with escapement mechanism intermediate said parts and with an escapement release for permitting the free travel of the movable one of said parts, of means for arresting the travel of said movable part embracing two members, one of said members having a plurality of column-field stops mounted upon one of said parts and the other of said members comprising means for dogging said stops and being mounted upon the other of said parts, one of said members being movable to engage the other, key mechanism whereby said dogging mechanism and said column-field stops may be caused to engage, said key mechanism comprising means connected to the movable member of the column-field stop mechanism and a lost-motion connection intermediate the key mechanism and the escapement release whereby the escapement is released after the movable member of the column-field stop mechanism is brought to position to engage the fixed member of said mechanism.

10. In a spacing mechanism for typewriting machines, the combination with a paper support and with a printing mechanism, one of said parts being movable with respect to the other in the direction of the line of print and with escapement mechanism intermediate said parts and with an escapement release for permitting the free travel of the movable part embracing two members, one of said members having a plurality of column-field stops mounted upon one of said parts and the other of said members comprising means for dogging said stops and being mounted upon the other of said parts, one of said members being movable to engage the other, key mechanism whereby said dogging mechanism and said column-field stops may be caused to engage, a connection between said key-mechanism and the movable member of the column-field stop mechanism, a connection between said key-mechanism and said escapement release and a spring arranged intermediate said escapement release and said key-mechanism, said spring being placed under tension by the actuation of said key-mechanism and serving to operate said escapement release.

11. In a spacing mechanism for typewriting machines, the combination with a paper

support and with a printing mechanism, one of said parts being movable with respect to the other in the direction of the line of print and with escapement mechanism intermediate said parts and with an escapement release for permitting the free travel of the movable one of said parts, of means for arresting the travel of said movable part embracing two members, one of said members having a plurality of column-field stops mounted upon one of said parts and the other of said members comprising means for dogging said stops and being mounted upon the other of said parts, one of said members being movable to engage the other, key mechanism whereby said dogging mechanism and said column-field stops may be caused to engage, a connection between said key mechanism and the movable member of said column-field stop mechanism, a connection between said key mechanism and said escapement release, a dog or pawl for holding said escapement release against movement and a connection between said key mechanism and said dog or pawl.

12. In a spacing mechanism for typewriting machines, the combination with a paper support and with a printing mechanism, one of said parts being movable with respect to the other in the direction of the line of print and with escapement mechanism intermediate said parts and with an escapement release for permitting the free travel of the movable one of said parts, of means for arresting the travel of said movable part embracing two members, one of said members having a plurality of column-field stops mounted upon one of said parts and the other of said members comprising means for dogging said stops and being mounted upon the other of said parts, one of said members being movable to engage the other, key mechanism whereby said dogging mechanism and said column-field stops may be caused to engage, a connection between said key mechanism and the movable member of said column-field stop mechanism, a spring connection between said key mechanism and said escapement release, a dog or pawl for holding said escapement release against movement and a lost-motion connection between said key mechanism and said dog or pawl.

13. In a spacing mechanism for typewriting machines, the combination with a paper support and with a printing mechanism, one of said parts being movable with respect to the other in the direction of the line of print and with escapement mechanism intermediate said parts and with an escapement release for permitting the free travel of the movable one of said parts, of means for arresting the travel of said movable part, embracing two members, one of said members having a plurality of column-field stops mounted upon one of said parts and the other

- of said members comprising means for dogging said stops and being mounted upon the other of said parts, one of said members being movable to engage the other, key mechanism whereby said dogging mechanism and said column-field stops may be caused to engage, said key mechanism comprising lever mechanism extending from back to front of the machine, a rock shaft mounted above 5 said lever mechanism and connected with the movable member of the column-field stop mechanism and with said lever mechanism, and a sleeve mounted upon said rock shaft, said sleeve being connected with the escapement release and with said lever mechanism.
14. In a spacing mechanism for typewriting machines, the combination with a power-propelled paper-carriage and with an escapement mechanism for controlling the step-by-step movement of said carriage, a plurality 10 of column-field stops mounted upon said carriage, a movably supported dog for engaging said column-field stops whereby said carriage may be arrested at any predetermined 15 column-field upon the paper, denominational stop mechanism whereby the orderly printing of rows of figures or the like may be effected, key mechanism for variably shifting said dog to cause it to engage any predetermined 20 one of said column-field stops, locking mechanism for temporarily retaining said dog in any one of its shifted position and means for releasing said locking mechanism operated by the means whereby the escapement 25 mechanism of the typewriter is controlled and operated also by the denominational stop mechanism.
15. In spacing mechanism for typewriting machines, the combination with a carriage, of means for arresting the travel of 30 said carriage comprising a series of stops and means for dogging said stops, a support whereon said series of stops are adjustably mounted and a longitudinally movable locking-bar on said support for temporarily holding 35 said stops against displacement.
16. In spacing mechanism for typewriting machines, the combination with a carriage, of means for arresting its travel comprising 40 a series of stops and means for dogging said stops, a bar having a series of seats whereon said series of stops are adjustably mounted and a locking-bar mounted to slide longitudinally on said stop supporting bar 45 for temporarily holding said stops in adjusted position.
17. In a spacing mechanism for typewriting machines, the combination with a paper-support and with a printing mechanism, one 50 of said parts being movable with respect to the other in the direction of the line of print, of means for arresting the travel of said movable part embracing two members, one of said members comprising a plurality of stops 55 having notches therein, a stop-bar whereon

said stops are mounted, and a locking-bar mounted upon said stop-bar and having a series of projections adapted to engage with the notched portions of said stops in order to retain said stops against displacement.

18. In a spacing mechanism for typewriting machines, the combination with a paper-support and with a printing mechanism, one of said parts being movable with respect to the other in the direction of the line of print, 75 of means for arresting the travel of said movable part embracing two members, one of said members comprising bifurcated stops, each having a notch in one of its arms, a notched stop-bar whereon said stops are 80 mounted, and a notched locking-bar or plate and means for shifting said locking-bar or plate to bring its notches co-incident with those of the stop-bar or out of line therewith and into the notches of the stops.

19. In a spacing mechanism for typewriting machines, the combination with a paper-support and with a printing mechanism, one of said parts being movable with respect to the other in the direction of the line of print, 90 of means for arresting the travel of said movable part embracing two members, one of said members comprising a plurality of bifurcated stops each having a notch in one of its arms, a stop-bar provided with notches to receive stops, and a sliding locking-bar formed with notches and projections, and means for shifting said locking-bar to bring either its notches or projections opposite the notches of said stops.

20. In spacing mechanism for typewriting machines, the combination with a carriage, an escapement and a release therefor, of means for arresting the travel of said carriage comprising two members, viz: a series 105 of stops and dogging means normally out of line, key mechanism for shifting one of said members in line with the other of said members, a lock for said shiftable member, means connected with said key-mechanism for actuating said escapement release, a second lock for said escapement release and a common release for both of said locks actuated by the printing mechanism of the machine.

21. In spacing mechanism for typewriting machines, the combination with a carriage and an escapement therefor, of means for arresting the travel of the carriage comprising a series of column-field stops and a dog for engaging said stops, a release-lever, 115 key mechanism for actuating said release lever and for variably actuating said dog to engage a predetermined one of said column-field stops, a locking-pawl for said dog, a second locking-pawl for said release-lever arranged to engage said first mentioned pawl and a trip connected to the printing mechanism for releasing both of said locking pawls.

22. In a spacing mechanism for typewriting machines, the combination with a 130

- paper-support and with a printing mechanism, one of said parts being movable with respect to the other in the direction of the line of print, and having means for propelling it in said direction, of variable brake mechanism for arresting the free run of said movable part, key mechanism for actuating said variable stop mechanism, a brake mechanism controlled by said key mechanism for checking the free run of said movable part and a device also controlled by said key mechanism for varying the force exerted by said brake mechanism.
23. In a spacing mechanism for typewriting machines, the combination with a paper-carriage and with variable stop mechanism and keys for controlling said stop mechanism, whereby the free run of said paper-carriage may be arrested at any one of a number of points, of a friction-brake, a lever for actuating said brake to check the free run of the paper-carriage, and means operated by said key mechanism for imparting variable pressure to said brake-lever independently of the variation in the finger pressure of the key mechanism.
24. In a spacing mechanism for typewriting machines, the combination with a power-propelled paper-carriage, of variable stop mechanism whereby the free run of said carriage may be arrested at any one of a number of predetermined points, key mechanism for actuating said variable stop-mechanism, and a variable brake also actuated by said key mechanism and serving independently of any variation of finger pressure to impart different degrees of resistance to the free run of said paper-carriage.
25. In a spacing mechanism for typewriting machines, the combination with a power-propelled paper-carriage, of variable stop-mechanism for arresting the free run of said carriage at any one of a number of predetermined points, key mechanism for actuating said variable stop mechanism, a brake for checking the free run of said paper-carriage, cam mechanism for variably actuating said brake.
26. In a spacing mechanism for typewriting machines, the combination with a power-propelled paper-carriage and with variable stop mechanism for arresting the movement of said carriage, of a brake for checking the free run of said carriage, a lever for applying said brake, a cam for variably actuating said lever, and key mechanism for controlling the movement of said cam.
27. In a spacing mechanism for typewriting machines, the combination with a power-propelled paper-carriage and with an escapement mechanism for imparting a step-by-step movement to said carriage, of stop mechanism for arresting the free run of the paper-carriage, key mechanism for operating said stop mechanism, and means for check-
- ing the overthrow of the escapement mechanism, comprising a cam controlled by the key mechanism that operates said stop-mechanism.
28. In a spacing mechanism for typewriting machines, the combination with a power-propelled paper-carriage, an escapement mechanism for imparting a step-by-step movement to said carriage and an escapement release, of brake mechanism for checking the free run of the paper-carriage, comprising an expandable brake-body arranged to contact with a part connected to the carriage and means for expanding said brake-body.
29. In a spacing mechanism for typewriting machines, the combination with a power-propelled paper-carriage, an escapement mechanism for imparting a step-by-step movement to said carriage and an escapement release, of brake mechanism for checking the free run of the paper carriage, comprising a brake wheel of elastic material arranged to contact with a part connected to the carriage and means for radially expanding said wheel to increase its frictional contact with said part.
30. In spacing mechanism for typewriters, the combination with a power-propelled carriage and with an escapement therefor, of a series of column-field stops having their contact faces out of line, a dog for engaging said stops, key mechanism for actuating said dog and releasing said escapement and adjustable lost motion connections between said key mechanism and said escapement release.
31. In spacing mechanism for typewriters, the combination with a carriage, of a series of column-stops having their contact faces out of line, a dog for engaging said stops to arrest the movement of said carriage, devices for variably actuating said dog to engage a predetermined one of said stops, a brake for said carriage and means controlled by said actuating devices for applying said brake with variable pressure.
32. In spacing mechanism for typewriters, a notched stop supporting-bar and a similar notched plate shiftably mounted on said bar for locking the stops in position.
33. In spacing mechanism for typewriters, the combination with a carriage, of means for arresting the travel of said carriage comprising a series of stops and means for dogging said stops, finger-key mechanism for shifting one of said members to engage the dog, an escapement for said carriage, a release for said escapement, an actuating spring for said release arranged to be placed under tension by said key mechanism and a locking pawl for said release arranged to be tripped by said key mechanism.
34. In a typewriting machine, the combination of a carriage, carriage-feed mechanism, tabulating devices for arresting the

travel of the carriage, a release for the carriage feed mechanism, key mechanism controlling said tabulating devices and a lost-motion connection between said key mechanism and said carriage release, whereby said tabulating devices are set in operative position before the carriage is released.

35. In a tabulating machine and tabulating mechanism, the combination of a carriage, selective columnating mechanism to stop the carriage at any one of a plurality of predetermined columnar positions after a single run thereof, means for locking said columnating mechanism in shifted position, denominational-stop mechanism for arresting the travel of the carriage in any one of a series of adjacent letter-space positions, and means controlled by the denominational stop mechanism for releasing said locking means.

36. In a typewriting machine and tabulating mechanism, the combination of a carriage, selective column-stop mechanism for arresting the carriage at any one of a plurality of columnar positions after a single run thereof, selective denominational stop mechanism for arresting the run of the carriage at any one of a series of adjacent letter-space positions, separate independent key mechanisms for controlling said column-stop mechanism and said denominational stop mechanism, means for locking said column stop mechanism in its shifted position and means for releasing said lock controlled by the operation of said denominational-stop mechanism.

37. In a typewriting machine and tabulating mechanism, the combination of a carriage, selective column stop mechanism for arresting the carriage at any one of a plurality of columnar positions after a single run thereof, denominational stop mechanism for arresting the run of the carriage at any one of a series of adjacent letter-space positions, means for locking the column stop mechanism in shifted position and means for releasing said lock controlled either by the operation of said denominational-stop mechanism or by the operation of a character key or space bar.

38. In a typewriting machine and tabulating mechanism, the combination of a carriage, carriage feed mechanism, selective column stop mechanism for arresting the carriage at any one of a plurality of columnar positions after a single run thereof, denominational stop mechanism for arresting the run of the carriage at any one of a series of adjacent letter-space positions, a release for said carriage feed mechanism controlled by said column stop mechanism and by said denominational stop mechanism, means for locking said column stop mechanism and said carriage release in shifted position and means controlled either by the operation of said carriage feed mechanism or said denominational stop mechanism for releasing said locking means.

39. In spacing mechanism for typewriters, the combination with a power propelled carriage and with an escapement therefor, of a series of column field stops having their contact faces out of line, dogging means for engaging said stops, a release for said escapement, and a set of finger keys, each connected to said dogging means and to said release to operate both when shifted in one direction, said keys being arranged to impart a variable throw to said dogging means and a uniform throw to said escapement release.

40. In spacing mechanism for typewriters, the combination with a power propelled carriage and with an escapement therefor, of a series of column field stops having their contact faces out of line, dogging means for engaging said stops, a release for said escapement, a set of finger keys, two key levers engaged and operated by said keys, one of said levers being connected to said dogging means and the other to said release, said keys being arranged to impart a uniform throw to the key lever connected to said release and a variable throw to the key lever connected to said dogging means.

LOUIS SCHLESINGER.
